BOB C. HOUGHTON, OF AUSTIN, TEXAS.

MECHANICAL COTTON PICKER.

Application filed July 14, 1927. Serial No. 205,678.

In the cotton growing districts it is customary to pick the cotton bolls by hand. This procedure, especially where large amounts of cotton are grown, requires a large number of hands, and always the work involved in the picking of the cotton is extremely heavy and laborious. Because of this fact, and because of the scarcity and increasing cost of labor, it has been found to be desirable to substitute mechanical means for manual labor. To fill this demand, many types of cotton pickers have been devised, but all of them are open to various objections, among which may be mentioned awkwardness of operation, uncertainty of performance, costliness of manufacturing with resulting high market price, excessive weight and considerable degree of difficulty in handling.

The present invention seeks to provide a mechanical picker which will be easily operated, relatively inexpensive to manufacture, and which will be positive in its operation, leaving a field of cotton cleanly picked.

The invention embodies a means for picking the cotton which comprises a rotary element adapted to engage the cotton boll, combined with suction for conveying the picked cotton to a collecting sack at the rear of the machine, which sack is supported on a weighing device which is adjusted to automatically trip when a predetermined weight of cotton is collected in the sack. It is thought that the rotary type of picker employed in the device of this application, which type of picker does not involve any enmeshing or entangling process, is new in itself, this resulting in the removal of the fiber of the boll from the stalk without mutilation of the fibers. Suction is not used except to convey the picked cotton to the collecting sack. Perfectly clean cotton is thus assured.

The invention will be more readily understood by reference to the accompanying drawings, in which

Fig. 1 is a side elevation of the machine,

Fig. 2 is a plan view of the same,

Fig. 3 is a detail view of the steering device,

Fig. 4 is a detail view of the means for transferring motion to the picking members,

Fig. 5 is a detail view, partly in section, of the picking means with associated air inlets for suction, 55

Fig. 6 is an enlarged view of the picking mechanism,

Fig. 7 is an end view thereof,

Fig. 8 is a modification of the picking mechanism shown in Figs. 6 and 7,

Fig. 9 is a fragmentary side elevation of the variable speed control mechanism.

Referring more particularly to the drawings, it will be seen that the machine is made up of a main frame 1, constituting the carrying frame for the various parts of the machine. The device is mounted on three wheels, as is evident from the drawings, the large wheel 2 serving as the traction unit of the device, the small wheels 16 carrying the weight of the rear portions of the device, and functioning further as will be herein-after described. It will be seen that the wheels are arranged similarly to a velocipede. The wheel 2 serves as the traction unit and carries a vertical shaft and the pinions 2^a and 2^b, the pinions providing means for varying the speed of travel of the machine. 75

The machine is driven by means of an internal combustion engine 3 of conventional type and of sufficient power to drive the machine at the desired rate of speed. The engine, or motor, 3 receives its fuel supply from the tank 5, or from any other convenient source. The motor 3 also drives the suction fan 4, of standard construction, the function of which is to draw the picked cotton through the hollow member, or conduit, 17, and to blow this cotton through the member 4^a into the bag 10^a, which is fitted to the weighing device 7. 80

Power is transmitted from the motor 3 by means of the sprocket chain 3^a which passes over the gear 13, which drives the wheel 12. The gear 13 is mounted on the shaft 12^a, carrying at one extremity the wheel 30^a, while at the other extremity is mounted a wheel similar in every respect to the wheel 30^b 95

12, this second wheel being designated 12^b. It will be seen that the shaft 12^a serves as an axle common to the wheels 12 and 12^b and the gear 23. It will be further seen that the operation of this gear 23 will cause the wheels 12 and 12^b to move in unison, the wheel 12 operating the suction device 4, while the wheel 12^b drives the picking mechanism, power to these mechanisms being transmitted by the chains 30^a and 30 which respectively engage the teeth of the wheels 12 and 12^b.

There is also mounted upon the shaft 12^a the gear 23, this operating a worm 23^a secured to the shaft 24. At the end of the shaft 24 there is secured the gear 25, which meshing with the gear 26^b, rotates the shaft 28^a which carries means, such as a pinion, not shown, which imparts rotary motion to a shaft which carries the gears 28 and 29 meshing respectively with the gears 2^a and 2^b carried by the wheel 2, the pinions 28 and 29 are made to selectively engage the gears 2^a and 2^b respectively through the operation of the clutch members or levers 27 and 29^a, the operation of which by the lever 26 will throw the pinions 28 and 29 into and out of contact with the gears as desired, the engagement depending upon the direction in which the lever 26 is moved.

As will be seen from Figures 1 and 9, the change in motive speed of the machine is effected by the operation of the handle 26, the operation of the handle causing the registration of pinions with the gears 2^a and 2^b, as will be hereinafter described. The handle 26 is in fact the operating member for a clutch 27, this being a bell crank, there being a pivot connection between the handle 26 and the crank 27, indicated as 27^a. The crank arms of the bell crank 27 are conveniently at right angles to each other, normally in substantially horizontal and vertical positions, the horizontal arm terminating in a housing 35 and being secured therein in any convenient manner which will permit sufficient freedom of motion to permit its being brought into effective action for the manipulation of the pinions through the construction to be described.

Connected to the crank 27 is a second clutch, or bell crank, 29^a, the connection being made at the point 27^a. The construction of the crank 29^a is similar to that of the crank 27. The horizontal arm of the crank 29^a is secured in the housing 37, similar to the housing 35, the connection again being in such a manner as will permit free motion of the arm within the housing. The housings 35 and 37 are loosely mounted on a shaft 38 so that the shaft 38 may freely rotate therein, the lower end of said shaft 38 being preferably enlarged as shown at 31 to assure retention in its bearing member, the shaft 38 being carried by the bearing

member 39 rigidly secured to the standard 8. It will be understood that the shaft 38 is in effect a continuation of shaft 28^a, rotary motion from the shaft 28^a being imparted to the shaft 38 through the gear 26^a. 70

Carried by the shaft 38 are the pinions 28 and 29, abutting the housings 35 and 37, respectively. These pinions 28 and 29 are adapted to mesh with the gears 2^a and 2^b, respectively, and are so spaced that they will engage their gears successively as they are lifted into position by operation of the handle 26, the action of this handle being communicated to the gears through the clutches, or cranks, 27^a and 27^b. For example, to propel the entire machine the handle 26 will be pulled up by the operator, bringing the pinion 29 into engagement with its gear 2^b; and by pulling the handle 26 still further upwardly, pinion 28 will mesh with its gear 2^a to effect change of speed. The pinions are held in their desired positions by any suitable means, as, for example, supports, such as are indicated at 40, these supports being of any convenient form, readily suggesting 90 itself to the manufacturer of the device. A convenient form, for example, is for member 40 to be in the form of a bar, and notched 95 suitably to serve to hold in place the clutch mechanism.

The numeral 33 represents the axle of the wheel 2, and a bearing 34 may be provided for the shaft 28^a. The housing for the shaft 28 is designated as 36, this member being largely optional except in so far as it confers protection and serves as a head for the frame 1. 100

It will thus be seen that motion is imparted to the wheel 2 by the motor 3, the wheel 2 serving as the traction unit. The machine is steered by means of the members 15 as shown in Figs. 1 and 3, the members 15 being pivoted at 15^a to the frame 1, there being a portion 15^b integral with the members 15, the member 15^b being bent upwardly 110 at its end to form a tongue adapted to fit into a slot in the member 15^a. This member 15^a is secured to the end of the portion of the frame carrying the wheel 2. As further shown in Fig. 3 when one of the arms 15 engages an obstruction such as a cotton plant, the members 15 will be deflected and the motion is transmitted to the member 15^a and thus to the wheel 2, so that the wheel 2 will be always kept in a substantially predetermined path between the rows of plants between which the wheel 2 is traveling, the wheels 16 being spaced properly between the rows between which the wheel 2 is moving. 110

As before mentioned, the chain 30 drives a gear or worm 11, which meshes with a differential driving mechanism comprising the gear 21 operating the members 21^a and 21^b as clearly shown in Fig. 4. Each of these 130

members 21^a and 21^b rotates a shaft 22 which in turn operates the picking mechanism. This picking mechanism comprises the rollers 20 and 20^a. As shown on Fig. 7, 5 one of these rollers is rotative, by virtue of the motion from the shaft 22, while the second roller 20 is adapted to rotate in the opposite direction through frictional engagement with cotton fiber engaged with 10 the roller 20^a. The rollers are mounted within an open protective housing 19, and the roller 20 is so mounted that it may be laterally displaced in the said housing by the provision of the projection 20^c at each 15 end of the roller loosely fitting into the slot 20^d in the housing 19. An eccentric 19^b is provided with a slot registering with the slot 20^d of the housing, the position of the eccentric being adjustable, the eccentric being held in position by the spring 20^e. It 20 will thus be seen that the frictional engagement of the rollers 20 and 20^a causes the rollers to rotate in opposite directions, and the engagement between the rollers is yielding to adapt the relative position of the rollers to the cotton bolls passing between the rollers, the amount of displacement of the roller 20 being determined by the position of the eccentric 20^b. Thus a firm grip 25 on any boll is always assured.

A modification of this arrangement may be had as illustrated in Fig. 8, wherein both rollers may be operated by means of shafts 22 and 22^b exactly as has been just described. 30 In such an instance the relative position of the rollers may be determined by the tension of a spring 20^e positioned at each end of the housing as shown in Fig. 8. It will thus be seen that a boll of cotton will be grasped 35 by the rollers, pulled from the stalk and passed back into the housing because of the relation of the rollers. When the cotton passes back into the housing it is transferred to the weighing bag as will now be 40 described.

Adjacent the roller, the housing 19 is provided with a plurality of apertures 19^a, the purpose of which will be hereinafter brought out. The housing 19 opens into the 45 hollow shaft 17 which is provided with flexible joints, or elbows, as shown at 18 and 18^a (Figs. 1 and 2), so that the angular position of the shaft 17 may be adjusted to bring the rollers to varying heights during 50 their operation. The shape of the beveled gears 21^a and 21^b permits the adjustment of the rotary shafts 22 to take position corresponding to the desired elevation of the member 17, the desired adjustment being 55 made without breaking the contact between the gears 21^a and 21^b with the gear 21. The member 17 serves as a conduit for the picked cotton and leads into the suction end of a 60 blower 4 of standard construction, the exit 65 of the conduit 17 being the portion 4^a of

the blower adapted to discharge the cotton into a sack placed upon the weighing device. It will be seen that there is provided an unbroken conduit 17 leading from the pickers and discharging into the collecting 70 and weighing sack. The blower 4 is actuated by the belt 30^a which fits over the teeth of the wheel 12, the belt 30^a also engaging with the teeth of the sprocket 14 secured to the driving shaft of the blower 4. Power is 75 thereby transmitted to the blower 4 from the motor 3, as will be apparent from Figs. 1 and 2, so that the cotton engaged by the rollers 20 will be drawn with speed and facility through the conduit 17 and discharged into the bag 10^a, the blower 4 imparting a strong suction through the conduit 17, the suction being intensified by the provision of the apertures 19^a in the housing 19, these apertures providing for the access 80 of an abundant supply of air to the housing and conduit.

This bag 10^a is held in receiving position on the weighing device 7, as shown in Fig. 1, the frame in which the bag rests being supported upon the knife edge 7^a, so that as the cotton fills the bag the frame 7 will tilt until it engages the member 6^c. This member 6^c is pivotally supported upon a knife edge 31^a secured to the frame 1 and is joined 90 to a member 6^a pivoted to the frame 1, the joining member being the portion 6^b. The member 6^b is pivotally connected at 6^c with the member 6^c, and at 6^d with the member 6^a. It will thus be seen that the members 6^a, 100 6^b and 6^c constitute a compound lever, the arm 6^a of which carries a weight 6 of any desired value, this value being determined by the amount of cotton desired to be weighed in the bag. Or the weight 6 may be 105 movable along the arm 6^a, which must then be graduated into successive values to give any desired weight of the bag and contents, as will be apparent and as is well known. When the desired amount of cotton is received in the bag, the effect of the weight 6 will be counteracted and the arm 6^c will be depressed until it rests against the frame 1 as will be apparent from Fig. 1. It will 110 thus be seen that a constant amount of cotton may be weighed into each bag and the weighing of each bag proceeds automatically, the removal of a filled sack and the insertion of an empty sack being speedily 115 accomplished as soon as the arm 6^c is thrown, so that the picking operation need not be interrupted during a material time interval. A supply of sacks may be kept in 120 readiness on the platform 10 as shown in Fig. 1.

While the steering of the machine as it passes between the rows of plants has been described before, it may here be reviewed and pointed out anew that the traction wheel 2 is maintained in a substantially straight 125 130

course along the rows of plants by means of the guiding arms 15. Further steering of the machine may be effected by providing means such as standard 9, as shown in Fig. 1, the standard being connected with the shaft connecting the wheels 16. To facilitate the steering, means such as a rope or cable 9^a may be attached to the standard 9, the position of which may be changed by applying a pull to the rope or cable 9^a. There are also standards 9^b, as shown in Figs. 1 and 2, the rope 9^a being guided against these standards by the members 9^c through which the rope 9^a passes. There may be provided such a rope and standard on each side of the machine, and the standards may be connected with a yoke as shown in Fig. 2. The ropes then pass to the steering means of the wheels 16, the said ropes being connected to the arms 16^b which are pivoted to the shaft 16^a connecting the wheels 16, and to the shaft 16^c, there resulting a movable connection between these members. A pull on either rope will be transmitted to the respective wheel 16, the position of which will be changed through the turning of shaft 16^a. The section shaft 22 may be conveniently held in position by the straps or cleats 22^a.

It will be understood that it is desired to comprehend within the scope of the invention such modifications and changes as may be necessary to adapt it to varying conditions and uses.

What is claimed is:

1. A mechanical cotton picker comprising the combination with a frame, of picking means, a conduit associated with the picking means adapted to convey picked cotton to a collecting point, means permitting the flexing of the said conduit in any desired predetermined position, and power means adapted to propel the picker in a plurality of desired predetermined motive speeds.
2. A mechanical cotton picker comprising the combination with a frame, of driving units mounted upon the frame, a picking head, co-acting picking rollers within the head adapted to be actuated through the said driving units, means actuated by the driving units for operating the said rollers, and a clutch actuated multi-speed propelling means adapted to propel the picker in a selected predetermined motive speed.
3. A mechanical cotton picker comprising the combination with a frame, of a source of power, driving units actuated by the source of power mounted upon the frame, a picking head, picking rollers within the head, rotary means actuated by the driving units for actuating the said rollers, and traction means actuated by the driving units and adapted to propel the picker in a selected one of a plurality of predetermined speeds.
4. A mechanical cotton picker comprising

the combination with a frame, of a conduit carried by the frame, a picking head, relatively smooth picking rollers within the head, the said head communicating with the conduit, a source of power, driving units actuated by the source of power, rotary means driven by the driving units for actuating the said rollers, a fan in the conduit, means operated by the said driving units for operating the said fan, and clutch controlled traction means actuated by the said driving units adapted to propel the picker at a selected one of a plurality of predetermined speeds.

5. A mechanical cotton picker comprising the combination with a frame, of a conduit carried by the frame, a picking head communicating with the conduit, cooperating smooth surfaced picking rollers in the picking head, means for actuating the said rollers, a fan in the said conduit, means for actuating the fan, a source of power carried by the frame, traction means adapted to propel the picker in a selected one of a plurality of predetermined speeds, and a common driving means actuated by the source of power for the picker, roller actuating means, fan actuating means and traction means.

6. A mechanical cotton picker comprising the combination with a frame, of a conduit carried by the frame, a picking head communicating with the conduit, means for actuating the said rollers, a fan in the said conduit, means for actuating the fan, a motor carried by the frame, and common driving means actuated by the motor for operating the picker, roller actuating means, and fan actuating means.

7. A mechanical cotton picker comprising the combination with a frame, of a motor carried by the frame, an exhaust conduit mounted upon the frame, suction means within the conduit, a picking head communicating with the said conduit, picking means within the said head, means for actuating the picking means, means for actuating the suction means, multi-speed traction means adapted to propel the picker at any selected one of a plurality of predetermined speeds, and common driving means actuated by the motor for the driving of the traction means and all of the aforesaid actuating means.

8. A mechanical cotton picker comprising the combination with a frame, of a motor carried by the frame, propelling means for the picker driven by the said motor, a flexible conduit carried by the frame, a picking head communicating with the conduit, picking means within the head, means for actuating the said picking means, a suction fan within the conduit to produce a suction there-through, common means actuated by the motor for driving the picking actuating means, the fan, and the propelling means for the picker, and clutch controlled means per-

mitting the operation of the picker propelling means at a selected one of a plurality of predetermined speeds.

9. A mechanical cotton picker comprising the combination with a frame, of a motor mounted on the frame, traction means for propelling the picker carried by the frame, a flexible conduit carried by the frame, a picking head communicating with the conduit, picking rollers in the picking head, the said picking head being provided with apertures adjacent the rollers, an exhaust fan in the conduit, common driving means actuated by the motor for actuating the said rollers, fan and traction means, and means mounted on the traction means for propelling the picker at a selected one of a plurality of predetermined speeds.

10. A mechanical cotton picker comprising the combination with a supporting frame, of a source of power connected therewith, a traction wheel operated by the source of power, the said wheel being provided with means for effecting variation in the motive speed of the machine.

11. A mechanical cotton picker comprising the combination with a supporting frame, of a source of power connected therewith, a traction wheel operated by the source of power, a standard carrying the said wheel, power transmitting means passing through the standard to the wheel, a plurality of pinions carried on the wheel, and clutch mechanism adapted to vary the speed of the picker.

12. A mechanical cotton picker comprising the combination with a supporting frame, of a source of power connected therewith, a traction wheel operated by the source of power and clutch and pinion means associated with the wheel for varying the motive speed of the machine.

13. A mechanical cotton picker comprising the combination with a supporting frame of a source of motive power for the picker carried by the frame, picking means operative from the said source of power, a flexible exhaust conduit communicating with the picking means, a fan in the said conduit operative from the said source of power and adapted to convey picked cotton from the picking means to an exhaust therefor, and means upon the frame for carrying a supply of receptacles to receive the cotton as it issues from the exhaust.

14. A mechanical cotton picker comprising the combination with a supporting frame, of a source of motive power for the picker carried by the frame, picking means operative from the said source of power, a flexible exhaust conduit communicating with the picking means, a fan in the said conduit operative from the said source of power and adapted to convey picked cotton from the picking means to an exhaust there-

for, means upon the frame for carrying a supply of receptacles to receive the cotton as it issues from the exhaust, means carried by the frame indicating the discharge of a predetermined amount of cotton from the conduit, and means operated by the said source of motive power for varying the motive speed of the machine.

15. A mechanical cotton picker comprising the combination with picking elements and a supporting frame, of a source of power connected therewith, a traction wheel actuated by the said source of power and adapted to propel the picker, and guide means carried by the wheel, the said guide means being adapted to maintain the said wheel in a predetermined path between adjacent rows of plants through contact with the said plants of the said adjacent rows.

16. A mechanical cotton picker comprising the combination with a supporting frame and picking elements carried thereby, of a source of power carried by the frame, a traction wheel actuated by the source of power and adapted to propel the picker, guide means carried by the wheel and adapted to maintain the wheel in a predetermined path, and supporting wheels carried by the frame and adapted to readily follow the course set by the traction wheel.

17. A mechanical cotton picker comprising the combination with a supporting frame and picking elements carried thereby, of a source of power carried by the frame, a traction wheel actuated by the source of power and adapted to propel the picker, the said traction wheel being mounted adjacent one end of the frame, guide means mounted on the wheel and adapted to maintain the wheel in a predetermined path, and supporting wheels pivotally mounted adjacent the other end of the frame and adapted to be readily adjusted to the course set by the traction wheel.

18. A mechanical cotton picker comprising the combination with a frame, of a motor carried by the frame, an exhaust conduit mounted upon the frame, suction means within the conduit, a picking head communicating with the said conduit, picking means within the said head, means for actuating the picking means, means for actuating the suction means, a multi-speed traction wheel mounted adjacent one end of the frame and adapted to propel the picker at any selected one of a plurality of predetermined speeds, common driving means actuated by the motor for the driving of the traction means and all of the aforesaid actuating means, guides carried by the traction wheel and adapted to maintain the wheel in a predetermined path, and supporting wheels mounted adjacent the other end of the frame and adapted to be readily adjusted to the course set by the traction wheel.

19. A mechanical cotton picker comprising the combination with a supporting frame, of a motor carried by the frame, a traction wheel actuated by the source of power and adapted to propel the picker, means for selectively varying the speed of the traction wheel, guide means carried by the wheel and adapted to maintain the wheel in a predetermined path, and supporting wheels carried by the frame and adapted to be readily adjusted to the course set by the traction wheels.

20. A mechanical cotton picker comprising the combination with a frame, of a source of power carried by the frame, a propelling wheel for the picker operated through the said source of power, picking means and conveying means also operated through the said source of power, and means for operating the propelling wheel at a selected one of a plurality of predetermined speeds, the said means comprising a plurality of gears carried by the said wheel, a movable shaft adjacent the wheel, a plurality of pinions mounted upon the shaft and adapted to selectively engage the said gears, means comprising a plurality of levers for positioning the said pinions and shaft, and means for imparting rotary motion to the shaft.

21. A mechanical cotton picker comprising the combination with a frame, of a source of power carried by the frame, propelling means for the picker operated through the said source of power, picking means and conveying means also operated through the said source of power, and means for operating the propelling means at a selected one of a plurality of predetermined speeds, the said means comprising a plurality of gears, a rotatable shaft, a plurality of pinions associated with the gears and carried by the shaft, a plurality of levers to operate the shaft and to selectively engage the pinions with the gears, and means for imparting rotary motion to the shaft and pinions to drive the propelling means.

In testimony whereof, I have affixed my signature this 5th day of July, 1927.

BOB C. HOUGHTON.
